UNITED STATES PATENT OFFICE.

MOSES SOLINGER, OF NEW YORK, N. Y.

MACHINE FOR CALENDERING PAPER.

SPECIFICATION forming part of Letters Patent No. 296,080, dated April 1, 1884.

Application filed February 1, 1884. (No model.)

To all whom it may concern:

Be it known that I, MOSES SOLINGER, of the city, county, and State of New York, have invented certain new and useful Improvements in Machines for Calendering Paper, of which the following is a specification.

This invention has reference to an improved machine for calendering or finishing paper at one or both sides and for registering the quantity of paper passing through the machine; and the invention consists of an upper hollow heated steel roll, an intermediate hollow heated steel roll, and a lower paper-roll, means for revolving the upper roll at greater speed than the intermediate roll, and means for winding and unwinding the paper.

It consists, secondly, of means for registering the number of sheets passed through the machine.

20 In the accompanying drawings, Figure 1 represents a rear elevation, partly in section, of my improved calendering-machine; and Figs. 2 and 3 are elevations of the same taken from opposite sides.

25 Similar letters of reference indicate corresponding parts.

A A represent the supporting-standards of my improved paper-calendering machine. The standards A A are provided with vertical 30 guide-recesses $a a$, for the bearings of the three calendering-rolls, the upper and intermediate steel rolls, B and B', and a paper-roll, B², which are arranged one below the other. The upper and intermediate rolls, B and B', are made 35 hollow, and provided with hollow axles b , that extend through their bearings b' . The lower roll, B², is made of a series of paper disks that are tightly compressed between the heads of the roll and then turned off true, so as to 40 form a solid smoothly-surfaced roll. The rolls B B' B² revolve in contact with each other, the pressure between the rolls being increased or decreased by means of weighted levers C, that are pivoted to the lower rear part of the 45 supporting-standards A A, and connected by upright pivot-rods C' with levers C', that are pivoted to the top part of the frame. The top levers, C', press upon the rounded-off upper ends of vertically-guided rods C², that 50 press upon the bearings b' of the upper roll, B. By adjusting the weights of the lower levers, C C, nearer to or farther away from their

pivots the pressure on the calendering-rolls B B' B² is diminished or increased. The hollow steel rolls B B' are heated by means of 55 central gas-jet pipes, d d', that pass longitudinally through the rolls, the air required for combustion being drawn in through the hollow shaft b at that end where the gas-pipe enters, and the products of combustion discharged through the hollow shaft b at the opposite end of the rolls. The gas-jet pipes d are connected in any suitable manner to the gas-supply pipes d', which latter have stop-cocks d', to regulate or shut off the supply of 60 gas. A certain quantity of air is drawn into the vertical gas-supply pipes d' through small openings d' above the stop-cocks d', as shown in Figs. 2 and 3, and mixed with the gas, so that the proper heating-jets are obtained. 65 The motion is transmitted to the calendering-rolls B B' B² from a power-shaft, D, by suitable transmitting gear-wheels, which are arranged in such a manner that a comparatively slow motion is imparted to the lower paper-roll, B², a quicker motion to the intermediate roll, B', and a still quicker motion to the upper roll, B.

The roll of paper to be calendered is placed 70 on a shaft, E, that turns in bracket-bearings at one end of the machine, said shaft being provided with a pulley, e, to which a brake-shoe, e', that is operated by a hand-wheel shaft, e², can be applied at will. The threaded end of the shaft e² engages a nut on the 75 shank of the brake-shoe, so as to apply it to or remove it from the friction-pulley of the unwinding-shaft E, as required. The paper is conducted from the unwinding-shaft E over the tension-rollers E', and from the same 80 through between the upper steel rolls, B B', if both sides are to be calendered, and between the intermediate steel roll, B', and the lower paper-roll, B², when one side only has to be finished. The paper is wound up in the usual 85 manner on a shaft, F, that receives its motion by transmitting gear-wheels f f' from the power-shaft D. The winding-up-shaft F is provided with a fixed friction-disk, f², and a laterally-movable disk, f³, the hub f⁴ of the latter being grooved and engaged by the fork-shaped end of a fulcrumed lever, f⁵. The opposite end of the lever f⁵ is engaged by the threaded end of a short hand-wheel shaft, f⁶,

- which turns in bracket-bearings of the supporting-frame, as shown in Fig. 1. The movable friction-disk f^3 is applied more or less tightly or released from the fixed disk f^2 , so as 5 to regulate the speed of the winding-up shaft. The end of the paper is clamped to the winding-up shaft in any approved manner, but so that the shaft can be withdrawn from the roll of paper after it has been wound up.
- 10 When continuous paper is to be calendered on the machine, the length of the same is registered by means of a registering mechanism of any approved construction. That shown in the drawings consists of a fixed dial, g , and 15 a pointer, g' , applied to a worm-gear, g^2 , said gear meshing with a worm, g^3 , at the end of a short horizontal shaft, g^4 , that turns in bearings of one of the standards A, the opposite end of the shaft being provided with radial 20 arms g^5 , that are successively engaged by a projecting pin or stud, g^6 , on the gear-wheel that imparts rotary motion to the lower paper-roll, B², as shown in Fig. 1.
- When sheets are to be calendered, they are 25 fed over a table, H, supported on detachable brackets H' at the feeding end of the machine, to a pair of feed-rolls, h h, one of which receives rotary motion by a belt-and-pulley transmission from the shaft of the paper-roll B². Back 30 of the upper feed-roll, h, is arranged on the table H a transverse deflecting-plate, h', that guides the sheet of paper upward and over a transverse roller, h², supported in bearings at the rear end of fulcrumed levers H², the front ends 35 of which are acted upon by springs h³. The sheet of paper is next taken up by the calendering-rolls B B', which exert a tension on the sheet of paper, that is stretched taut between the feed-rolls h h, roller h², and calendering- 40 rolls B B'. The levers H² are thereby lowered, and a pawl, h⁴, pivoted to the rear end of one of the levers H², dropped into a ratchet-wheel, h⁵. When the sheet has passed over the roller h², the springs h³ raise the levers H² and cause 45 thereby the turning of the ratchet-wheel for the distance of one tooth. The shaft of the ratchet-wheel h⁵ actuates, by a transmitting worm wheel and gear, h⁶ h⁷, a pointer, h⁸, that indicates on a dial, h⁹, the number of sheets 50 which have passed through the machine. In this manner the sheets that are calendered on the machine are registered in a regular manner. The feed-table and the entire registering mech-

anism may be removed or applied to the standard A at a level with the paper-roll B², in which latter case the sheets are calendered on one side only.

I am aware that heated pressure-rolls have been used heretofore for calendering paper and other fabrics, and I therefore do not claim the same broadly; neither do I claim the device for registering the length of the continuous paper-roll passing through the machine, as such registering devices are old and well known; but I do claim the combination of heated calendering-rolls with a lower revolving paper-roll, whereby paper may be calendered at one or both sides, and also the device by which single sheets may be registered.

Having thus described my invention, I claim as new and desire to secure by Letters Patent—

1. In a paper-calendering machine, the combination of a heated pressure-roll, intermediate heated roll, and a lower paper-roll, with means for unwinding and with means for winding up the paper, whereby the paper may be finished at one or both sides, according as the same is passed between the lower and intermediate rolls, or between the upper and intermediate rolls, substantially as and for the purpose set forth.

2. In a paper-calendering machine, the combination of an upper heated pressure-roll, an intermediate heated roll, a lower paper-roll, means for unwinding the paper, means for winding up the paper, and friction-brakes applied to the unwinding and winding-up shafts, whereby the paper is moved at a properly-regulated speed through the calendering-rolls, substantially as set forth.

3. The combination, with the calendering-rolls, of a sheet-registering mechanism consisting of a feed-table having revolving feed-rolls, deflecting-plate back of the feed-rolls, tension-roller supported on oscillating and spring-acted levers, and means whereby the oscillations of the levers are transmitted to a registering dial and hand, substantially as set forth.

In testimony that I claim the foregoing as my invention I have signed my name in presence of two subscribing witnesses.

MOSES SOLINGER.
